UNITED STATES PATENT OFFICE.

OSSIAN A. HEDENGREN, OF TAUNTON, MASSACHUSETTS.

FIRE-BOX GRATE.

Application filed August 31, 1921. Serial No. 497,218.

To all whom it may concern:

Be it known that I, OSSIAN A. HEDENGREN, of Taunton, in the county of Bristol and State of Massachusetts, a citizen of the

United States, have invented a new and useful Improvement in Fire-Box Grates, of which the following is a specification.

My improvement relates especially to the fire box of a stove and it consists essentially in a construction whereby the grate bars are hung so that they may not only be rotated or oscillated to clean the fire box, but may be swung out of the way to dump the ashes. It will be evident to one skilled in the art that this desirable result may be secured in a variety of ways differing from each other only in mechanical details, and yet embody the invention as set forth in my claims.

I have shown in the drawings the preferred embodiment of my invention as applied to a stove.

Fig. 1 is a horizontal section of a stove embodying my invention taken on line 1—1 of Fig. 2, the grate being in place and part of the bed plate being indicated in dotted lines.

Fig. 2 is a front view, a portion of the journal plate being broken away to show the operating parts and the door being omitted.

Fig. 3 is a front view showing the journal plate.

Fig. 4 is an end elevation, the journal plate being removed and the parts being in dumping position.

Figs. 5 and 6 are vertical sections on lines 5—5 and 6—6, respectively, of Fig. 1.

Fig. 7 is a diagrammatic section to illustrate the operation of the invention.

The iron walls 1 of the stove and the door 150 may be of any desired construction or shape and enclose the linings 2 and bed frame 3. 6 is a cover plate.

As shown the bed frame has sockets 4 cast in its rear end and in these sockets 4 lie the rear ends of two side bars 5, 51, the front ends of which pass through the front 71 of the stove and the iron lining 7.

As shown these side bars 5, 51, are nearly circular in cross section, but have projections 52 at intervals thereon and each carries at its rear end an arm 8 having a bearing 9 at its free end (see Figs. 5 and 6).

The grate bars have rear circular ends 10, each of which is provided with a lug 11

adapted to limit the movement of the grate bar in the bearing, which is slotted or cut away to provide shoulders 12 for this purpose. The lugs also prevent the grate bars 60 from sliding rearwardly in the bearings.

The grate bars may be of any desired shape to provide a proper grid to hold up the fuel. The grid portion of each bar comprises portions 102 preferably triangular in cross section separated by triangular supporting sections 103, each of said portions 102 being substantially flat on the side 104 which is intended to carry the fuel, the other two sides 105 being suitably shaped to 70 assist in ridding the fire of the clinkers and ashes when the grate bars are shaken. The supporting sections 102 are arranged to register with the projections 52 of the side bars 5, 51. It will be understood that the precise shape of these various parts is immaterial so long as they support the fire properly and when shaken clear the fire.

The front ends of these grate bars also pass through openings in the front 71 of the 80 stove and each carries at its front end, which is irregularly shaped as at 108, a segment gear 13 having an opening correspondingly shaped, the two segment gears meshing, one of the grate bars 10 being shaped as at 106 85 to receive the ordinary crank handle (not shown), this construction being such that the oscillation of one bar 10 by the crank handle will shake both bars in the ordinary way. The front end of each bar carries a 90 lug 107 to prevent it from sliding, and said front end of each bar is journaled in one end of an arm 14, the other end of which is fixedly attached to a side bar 5 or 51, said bars being provided with lugs 55 which set 95 into openings in the arms 14 so that the said bars and segments will be turned together, the outer end of the side bar 5 being constructed as at 53 to receive and be turned by a crank handle. A collar 54 is carried 100 by each side bar to hold it in place, the arm 14 resting between these collars and the cover plate 6.

Each arm 14 carries a segment gear 56, these gears being arranged to intermesh and the front stove plate 71 has slots 61 to allow the side bars to be put into place, and also segmental slots 62 in which the grate bars move when they are swung downward to dump the ashes.

The cover plate 6 is suitably shaped to cover these various parts and is held against

the stove front by buttons 16, said cover plate being supported on lugs 15. Through the cover plate passes a stud 17 carrying at its inner end a finger 18 adapted to reach 5 between the teeth of one of the segments 56 so as to lock it in place, and at its other end a handle 19 outside the cover plate by which the finger may be moved. Stops 191 limit the movement of the handle 19.

19 The cover plate may have openings as shown for the ends of the grate bars and as shown has a housing 20 having an opening for the shaking handle, said housing being provided with a pivoted cover 21 to 15 be opened when the grate is to be shaken. The housing is shaped to cover one of the slots 62.

I prefer to provide the rear part of each segment 13 with a guiding surface 130 which 20 engages with a corresponding surface 600 on a fixed part of the frame and so is kept in such position during the dumping operation that when the grate bars are raised into supporting position their surfaces 104 25 will be in proper position to support the fuel. In other words the contacting surfaces 130 and 600 prevent or limit turning movements of the grate bars so that they 30 cannot become misplaced when lowered for dumping and so that when their carrying arms 8 are again moved upward said bars will be in such positions that the surfaces 104 will be uppermost, as shown in Fig. 4.

The operation of my invention is simple 35 and it is believed will be understood from what has been said above. So far as the grate bars are concerned, they may be of any desired construction and operated in any desired way. The main novelty of my construction lies in the fact that the grate bars which normally close the bottom of the fire 40 box and may be rotated or oscillated in the usual manner, may be displaced when it is desired to dump the fire so as to expose substantially the entire opening at the 45 bottom of the fire box and allow the contents of the fire box to fall into the ash pan below. As shown this is accomplished by supporting the grate bars in swingable arms 50 carried by turnable side bars but I do not mean to limit my invention to this specific construction nor do I limit myself to the specific means for holding the parts in fuel supporting position for other equivalent 55 means of embodying the invention set out in the claims will occur to those skilled in the art.

What I claim as my invention is:

1. A rocking and dumping grate for fire boxes comprising suitable supports, two side 60 bars pivotally mounted in said supports and provided with arms extending inward towards each other and with intermeshing segment gears, and grate bars pivotally mounted in said arms and also provided 65 with intermeshing segment gears.

2. A rocking and dumping grate for fire boxes comprising suitable supports, two side bars pivotally mounted in said supports and provided with arms extending inward 70 towards each other and with intermeshing segment gears, grate bars pivotally mounted in said arms and also provided with intermeshing segment gears, means whereby 75 said grate bars may be rocked in their bearings in said arms to shake the grate, and means whereby said side bars may be turned in their bearings in said supports to move the grate bars bodily downward away from each other in dumping. 80

3. A rocking and dumping grate for fire boxes comprising suitable supports, two side bars pivotally mounted in said supports and provided with arms extending inward towards each other and with intermeshing 85 segment gears, grate bars pivotally mounted in said arms and also provided with outer meshing segment gears, means whereby said grate bars may be rocked in their bearings in said arms to shake the grate, 90 means for limiting the rocking movement of said grate bars in their bearings in said arms, and means whereby said side bars may be turned in their bearings in said supports to move the grate bars bodily 95 downward away from each other in dumping.

4. A rocking and dumping grate for fire boxes comprising suitable supports, two side bars pivotally mounted in said supports 100 and provided with arms extending inward towards each other and with intermeshing segment gears, grate bars pivotally mounted in said arms and also provided with intermeshing segment gears, means whereby 105 said grate bars may be rocked in their bearings in said arms to shake the grate, means whereby said side bars may be turned in their bearings in said supports to move the grate bars bodily downward away from 110 each other in dumping, and means for maintaining said grate bars in proper positions during dumping operations.

OSSIAN A. HEDENGREN.
